[57] CLAIM

The ornamental design for a electronic conductive contact sensor, as shown and described.

DESCRIPTION

FIG. 1 is a front-top perspective view of an electronic conductive contact sensor, showing my new design;

FIG. 2 is a top plan view thereof;

FIG. 3 is a front elevational view thereof;

FIG. 4 is a bottom plan view thereof;

FIG. 5 is a rear elevational thereof; and

FIG. 6 is a left-side elevational view thereof, the right-side elevational view being a mirror image.
